UNITED STATES PATENT OFFICE.

JAMES WOLSTENHOLME, OF BUFFALO, NEW YORK.

APPARATUS FOR BURNING FUEL.

SPECIFICATION forming part of Letters Patent No. 234,448, dated November 16, 1880.

Application filed July 22, 1880. (No model.)

To all whom it may concern:

Be it known that I, JAMES WOLSTENHOLME,
a citizen of the United States, residing in the
city of Buffalo, in the county of Erie and State
5 of New York, have invented certain new and
useful Improvements in Apparatus for Burn-
ing Fuel, of which the following is a specifica-
tion.

My invention relates to certain mechanism whereby a more perfect combustion is provided for; and it consists of one or more air-pipes having their inlet-openings in the outer or free air, and connected with a pipe or coil or a series of pipes having their outlet-openings terminate in an opening arranged within the furnace at an angle to the path of the gases, in combination with a substantially air-tight combustion-chamber, as and for purposes which will be more clearly hereinafter shown.

will be more clearly understood when seen.

20 In the accompanying drawings, Figure 1 represents a vertical longitudinal section through a steam-boiler, showing a side elevation of my invention as connected thereto. Fig. 2 is a top view of a modified form of the coil of pipe; Fig. 3, a plan or top view of a portion of Fig. 1. Fig. 4 is a vertical section through the center of a chimney, showing a portion of a chimney and a front view of the pipes as arranged therein, a part of the upper portion of the central pipe being in section. Fig. 5 is a vertical central section through a portion of a chimney and central tube, and Fig. 6 represents a vertical central section through a modification of my invention.

35 A represents the chimney, such as is usually employed, in which I arrange one or more tubes, B, having an opening or mouth, C, into which the cold air enters in the direction of the arrows, into the tube or flue B, and from
 40 thence into and down the flue or tube D, where it receives a portion of the heat that is usually lost by passing up the chimney, and it then passes into and through a coil, E, surrounding the fire-chamber, in which case the pipe would
 45 be connected with the coil in the usual way, and the bell-shaped mouth H, as shown in Fig. 1, would be placed at the point C, shown in Fig. 4. (See Figs. 1, 2, and 3, in which Fig. 2 represents a modification of the coil, composed of straight lengths of pipe F, held to-
 50

gether by curved elbows made in the usual way.) The air, after it becomes sufficiently heated, issues from a long narrow opening, G, in the combustion or fire chamber, (see Figs. 1, 2, and 3,) which opening is arranged at an angle to the direction of the furnace-draft, where it meets the gases from the fire or fuel, and a more perfect combustion takes place. The products of combustion take the usual course to the chimney through the boiler or other device with which my invention may be combined. 55 60

I do not confine myself to the precise arrangement shown, as there may be one or more tubes, B, and in some cases the tubes in the chimney may be dispensed with and the coil E may terminate in a flaring mouth-piece, H, arranged directly under or near the furnace or boiler, (see Fig. 1,) the object being to have the column of fresh air heated up to as near the temperature of the gases as possible when it issues from the opening G. The induced upward current of air in the tubes B is sufficient to force the more heated air through the various tubes mentioned, while the draft of the chimney assists, as will be readily understood. 75

My invention is as well adapted to a stove as to a tubular or other boiler or furnace.

I sometimes introduce steam as an auxiliary 80 into the air-conductors at a point after the air has become heated to about an even temperature with it, which, becoming mixed with said air, issues from the opening G, as above stated.

My object in placing the head of the columns of air within the chimney with their feet at the bottom or near the ground is to obtain from it without cost the maximum of heat passing off there. The same is the object of placing the tubes containing the balance of the column under or around the fire-box. Of this, however, there is nothing arbitrary. The place, the position, the caliber, and length of the column will vary with the circumstances to which it will have to conform; but it is arbitrary that it shall be always a closely-confined column, having its commencement in the outer air at some convenient point as near the ground as practicable, and having its issue at a point in the furnace in a direction reciprocally across 85 96 95 100

the path of the gases. The form may also be adapted to the circumstances to be met—the heating to a high but indefinite heat and conveying said heated air to meet the uncom-busted inflammable gases between the furnace 5 and the object of the fire for the purpose of expanding said gases so as to obtain the maximum of their heating power for any purpose, and the arrangement of the way in which that 10 point is obtained varying, as it must, with the kind of furnace to which it is applied, which furnace may be formed of any suitable material, and receiving its air from a column having its base in the open air, subject to the circumstances of its use, whether it be stationary, 15 steamboat, or other uses, or stoves of any kind, and having the issuing-point for the hot air, as before specified.

In the modified form shown in Fig. 6, instead 20 of the coil, as shown in Figs. 1 and 3, a cone-shaped case, L, is shown, having its inlet or mouth in the free air outside at M and its issue inside at N, the air passing up through the annular space O and out at N, for the purposes before mentioned. The door J of the 25 furnace should be made to fit closely without a damper or opening of any kind, so that no air shall pass in except the heated air through the

opening G and that which passes up through the grate K and fuel. 30

By having the furnace-door as nearly air-tight as practicable, so that no air can get in except that which passes in through the grate and opening G, the draft of the chimney can act to much better advantage in drawing the 35 fresh heated air through the opening G, and thereby force a strong blast of fresh heated air into the combustion-chamber at the proper point to produce a more perfect combustion without the aid of a blower or any other air-forcing device. 40

I claim as my invention—

A furnace or other heating device having the usual chimney for producing the necessary draft, a substantially air-tight door, and the 45 usual open grate for admitting air to the fuel, in combination with a tube or coil having its inlet-opening in the outer air and its outlet end terminate in a long narrow opening, G, adapted for conducting the heated air across 50 the path of the gases in their course to the chimney, as specified.

JAMES WOLSTENHOLME.
